UNITED STATES PATENT OFFICE.

RALPH W. AUSTIN, OF QUINCY, MASSACHUSETTS.

FIRE EXTINGUISHER.

Application filed September 20, 1922. Serial No. 589,355.

To all whom it may concern:

Be it known that I, RALPH W. AUSTIN, a citizen of the United States, residing at Quincy, in the county of Norfolk and State 5 of Massachusetts, have invented certain new and useful Improvements in Fire Extinguishers; and I do hereby declare the following to be a full, clear, and exact description of the invention, such as will enable others skilled in the art to which it 10 appertains to make and use the same.

This invention relates to a fire extinguisher.

The invention has for an object to provide a novel and improved fire extinguisher of the type employing liquid chemicals for the generation of the gas pressure for expelling the extinguishing liquid, which is capable of operating with high efficiency 20 at low temperatures.

A further object of the invention is to provide a fire extinguisher of the character specified which is capable of operating under all conditions of use at maximum efficiency.

With these objects in view the invention consists in the fire extinguisher and compounds for use in a fire extinguisher, hereinafter described and particularly defined 30 in the claims at the end of the specification.

The drawing illustrates an extinguisher embodying the present invention and in which Fig. 1 is a vertical section and Fig. 2 is a detail on line 2-2 of Fig. 1.

In the usual form of fire extinguisher at present upon the market, the carbon dioxide gas utilized for expelling the extinguishing liquid is generated by the reaction of sulphuric acid upon a solution of 25 bicarbonate of soda. The soda and acid solutions are normally isolated from one another to be capable of mixture when the extinguisher is inverted. When such form of extinguisher is exposed to low temperatures, even the ordinary low temperatures 40 encountered in the use of the extinguisher in the winter, as for example, the temperatures between the freezing point of water and zero F., the bicarbonate of soda starts 45 to precipitate out of the solution when the latter is cooled to approximately 27° F. As the temperature of the solution is lowered, increasing quantities of the bicarbonate precipitate out so that the efficiency of the extinguisher is soon decreased to such a point 50 as to impair its practical operation. As the

concentration of the soda decreases, the liquid soon freezes, causing rupture of the outer container. At zero F. the extinguisher is in fact actually inoperative. 60

The only approved form of anti-freezing fire extinguisher at present upon the market utilizes chemicals in solid form for generating the gas pressure to expel an anti-freezing extinguishing liquid such as concentrated calcium chloride solution. In practice this form of fire extinguisher has not met with favor by the trade, being regarded unsatisfactory for various reasons, particularly because of the explosive nature of the solid chemicals employed and the uncertainty of the reaction between the chemicals. Attempts have also been made to produce a commercial anti-freezing extinguisher employing liquid chemicals, but 75 at the present time so far as I am aware, with the exception of an extinguisher embodying the features of the present invention, no anti-freezing extinguishers employing liquid chemicals have been approved by 80 the National Board of Fire Underwriters or are found upon the market at the present time.

In approaching the problem of the production of a commercial anti-freezing extinguisher employing liquid chemicals, potassium carbonate was selected as the basic chemical for the production of the carbon dioxide gas for the reason that of all of the soluble carbonates, ammonium carbonate, sodium carbonate, and potassium carbonate, the latter possessed a eutectic point in the pure form of -36° C. whereas the eutectic point of the sodium carbonate was -2° C. Ammonium carbonate or bicarbonate because of their volatility and instability under slight heat and pressure, were found to be entirely unsuitable for practical use in an extinguisher. The National Board of Fire Underwriters require 90 for an A-1 rating that the extinguisher be capable not only of withstanding a temperature as low as -40° C. but that it should be capable of operating with high efficiency at such temperature and be able 95 to develop pressure sufficient to throw an extinguishing stream at least 40 feet. 100

In practice with the commercial grades of potassium carbonate obtainable, it was found impossible to obtain a potassium carbonate 110 solution which would remain fluid at the temperature corresponding to the theoretical

eutectic point, while the character of the crystallization occurring was such that the mass assumes a sort of semi-viscous state lacking the characteristic expansion of ice, and which as the temperature was lowered, becomes granular. This characteristic of the potassium carbonate solution of itself eliminates the liability of subjecting the extinguisher to bursting strains, thus contributing to the durability of the extinguisher. A large number of reagents were experimented with in the attempt to find one which when dissolved in the potassium carbonate solution would produce a composition having a eutectic point -40° C . All the organic materials which were suitable in this respect were found to require, because of their high molecular weights, the use of such a large quantity of the reagent as to preclude the possibility of using them in fire extinguishers of the size commonly used in practice. Of the inorganic reagents, all of those experimented with, with the exception of the hydroxides, were found unsuitable for either one of two reasons:—that they either formed an insoluble precipitate in the form of a carbonate or hydroxide, examples of such reagents being copper chloride, calcium chloride, iron chloride and zinc chloride, or for the additional reason that they reacted with the carbonate to form the soluble chloride or salt such as potassium chloride, the eutectic points of which solutions were relatively high. The eutectic point of potassium chloride being -11° C ., it is obvious that the eutectic point of potassium carbonate itself could not be lowered by reagents which form salts, such as potassium chloride, in the solution.

Potassium hydroxide, having a eutectic point of -65° C ., was found to lend itself admirably for use with potassium carbonate solutions, not only because of its low eutectic point but also because of the fact that it produced a common ion in solution, eliminating the formation of objectionable salts such as potassium chloride. In addition, as will be pointed out, the potassium hydroxide assists materially in producing an extremely rapid reaction between the acid and the carbonate at the low temperatures, thus assisting the instantaneous development of high pressure at low temperatures and enabling the extinguisher to operate with high efficiency.

For the production of an anti-freezing extinguisher, it is necessary to employ an acid which is likewise capable of withstanding the low temperatures without freezing, and it has been found that sulphuric acid of concentrations by weight between the limits of 65.25% and 74.5% possess freezing points of -40° C . and lower. It is preferred to employ a sufficient quantity of sulphuric acid of a concentration by weight of 74.5%,

to completely neutralize the potassium hydroxide and react with the potassium carbonate.

In the preferred form of extinguisher, an extinguishing liquid comprising a solution of calcium chloride of sufficient concentration to be capable of remaining liquid when exposed to a temperature of -40° C . is employed. The carbonate solution is preferably made up in proportions corresponding to 2 lbs. of potassium carbonate dissolved in 3 lbs. of water and to which $\frac{2}{3}$ lb. of potassium hydroxide is added. A sufficient quantity of 74.5% by weight sulphuric acid is preferably employed. The carbonate and acid solutions are normally isolated and may be contained in separate containers.

Referring to the drawing, the extinguisher illustrated therein comprises a metal container 10 of usual shape having the usual opening 12 in the top thereof through which the charge of extinguishing materials are introduced, and having an outlet or discharge nozzle 14 of usual construction. The opening 12 is normally closed by a metal cap (not shown) screwed upon the threaded neck of the container 10. The container 10 is normally filled to approximately the indicated level with an anti-freezing solution, which may and preferably will comprise a water solution of calcium chloride of sufficient concentration to withstand temperatures between -40° F . to -55° F .

The carbonate solution, preferably potassium carbonate solution, containing the potassium hydroxide, and the sulphuric or other acid necessary for the generation of the gas pressure for the operation of the extinguisher are normally maintained within the container 10 in separate containers 22, 24, the latter being supported within the former and both being normally maintained in a position such as to prevent mixture as long as the extinguisher is held upright or in the position illustrated in Fig. 1. The container 22 comprises an annular metal receptacle of the shape illustrated in Fig. 1, preferably of brass, and which is secured to and supported by a ring 21 resting upon a shelf 25 projecting inwardly from the neck of the container as shown. A cap member 28 is screwed into the ring 21, normally closing the container 22. In the preferred manner of construction, the container 22 comprises a brass tube within which the second tube 23 is positioned, the latter being supported at its bottom upon a tube 30, soldered or otherwise secured to the bottoms of the tubes 22, 23, and arranged to register with preformed holes in the bottoms of these tubes to form a passage from the interior of the tube 23 through the lower part of the tube 22, for a purpose to be described. The sulphuric acid is contained in a separate container 24, preferably comprising the

usual bottle, and which is supported by indentures 26 projecting from the tube 23, and retained in a centralized position by similar indentures 29 arranged to engage the sides 5 of the bottle. The sulphuric acid bottle 24 is provided with the usual form of lead stopper to normally close the mouth thereof while the extinguisher is in upright position. The stopper is provided with the usual 10 shank extended down into the bottle and of sufficient length to center the stopper when the extinguisher is inverted and the stopper has fallen against the bottom of the cap 28. Guard members 36 are arranged to depend 15 from the bottom of the cap 28 and to engage the body of the sulphuric acid bottle in order to removably retain it within its container. The ends of arms 37 extended laterally from the guard members 36 are 20 arranged to hook over the tube 23 to support the top thereof. The tubes 22, 23, bottle 24, cap 28 and ring 21 constitute a unitary structure, which may be easily removed from the extinguisher casing. These parts are 25 normally retained in position upon the shelf 25 by gravity and by the extinguisher cover (not shown) which is screwed onto the neck of the extinguisher.

From the description thus far, it will be 30 observed that the carbonate solution forming the basis from which the carbon dioxide gas is generated is retained in such position that when the extinguisher is inverted, the carbonate solution flows downwardly from 35 the interior of the container 22 through the annular passage surrounding the tube 23 into a chamber 38 which may be regarded as a mixing chamber. The sulphuric acid from the bottle 24 at the same time flows directly 40 into this mixing chamber 38. As the carbon dioxide gas is generated, it is caused to pass through the annular passage between the interior of the tube 23 and the sides of the bottle 24 and thence through the tube 30 to 45 the bottom of the extinguisher, it being understood, of course, that the extinguisher being in an inverted position, the carbon dioxide gas rises in the manner described through the space between the bottle 24 and 50 tube 23 through the tube 30 into the air space above the extinguishing liquid within the container 10. The development of a large gas pressure above the extinguishing liquid serves to effectively force it through 55 the outlet nozzle 14 in the desired stream. With this construction it will be observed that the mixing of the sulphuric acid and carbonate solution is caused to take place in a chamber separated from the outlet or 60 discharge nozzle 14 so that there is no liability of the extinguishing stream issuing from the nozzle 14 containing any sulphuric acid.

In the operation of the extinguisher and 65 particularly at very low temperatures, when

the extinguisher is inverted as the acid flows into contact with the carbonates and hydroxide solution, a large quantity of heat is immediately developed, because of the reaction between the acid and the hydroxide 70 according to the following equation:

The development of this large quantity 75 of heat immediately raises the temperature of the reacting materials, causing the rate of the reaction between the acid and the carbonate to be raised to a point such that the desired gas pressure is almost instantaneously built up within the extinguisher, thus enabling the extinguisher to operate 80 immediately after it has been inverted with maximum efficiency. The presence of the potassium hydroxide in the carbonate solution is also important in that it retains the carbonate in solution even when the extinguisher is exposed to extremely low temperatures such as are encountered in the 85 northern countries, such as Canada. 90

While it is preferred to employ potassium carbonate and potassium hydroxide as the basic chemical for reaction with an acid to produce carbon dioxide gas in the extinguisher, it is not desired to limit the invention in this respect for the reason that the use of a hydroxide in connection with sodium carbonate is of advantage in respect to the development of heat by the reaction 95 of the acid and hydroxide and which results in increasing the rapidity of the reaction between the acid and the carbonate, thus enabling the desired gas pressure to be built up instantaneously. In addition, of course, the development of the heat within the extinguisher operates to increase the pressure 100 which would otherwise be formed from a given quantity of reacting materials, so that in this respect the extinguisher is enabled to throw a stream a greater distance than 105 otherwise would be the case were not the hydroxide to be used. 110

Having thus described the invention, what is claimed is:

1. In a fire extinguisher, an anti-freezing extinguishing liquid capable of withstanding a temperature of -40° F. without freezing, and chemicals in liquid form for expelling the extinguishing liquid comprising a normally isolated solution of sulphuric acid and a normally isolated solution of potassium carbonate containing potassium hydroxide, the concentration of the sulphuric acid solution and the proportions of potassium carbonate and potassium hydroxide in 120 the carbonate solution being such that both solutions remain fluid at a temperature of -40° F. 125

2. In a fire extinguisher, an extinguishing liquid capable of withstanding a tempera- 130

ture of -40° F. without freezing, a normally isolated acid solution capable of withstanding a temperature of -40° F. without freezing, and a normally isolated solution of potassium carbonate containing potassium hydroxide in the proportions of 2 lbs. of potassium carbonate and $\frac{1}{2}$ lb. potassium hydroxide in 3 lbs. of water.

3. In a fire extinguisher, an anti-freezing extinguishing liquid, and chemicals for expelling the extinguishing liquid including a normally isolated acid solution capable of withstanding a low temperature without freezing and a normally isolated potassium carbonate solution containing a potassium hydroxide solution.

4. In a fire extinguisher, in combination, an anti-freezing extinguishing liquid, a normally isolated sulphuric acid solution of a

concentration between 74.5% and 65.25% by weight, and a normally isolated mixture of potassium carbonate and potassium hydroxide solution in the proportions of 3:1.

5. In a fire extinguisher, a normally isolated acid solution and a normally isolated carbonate solution containing an hydroxide in solution.

6. A carbonate solution for fire extinguishers comprising as essential ingredients, potassium carbonate and potassium hydroxide said ingredients being in sufficient amounts that the carbonate solution will not freeze at about -40° F.

7. A carbonate solution for fire extinguishers comprising as essential ingredients potassium carbonate and potassium hydroxide substantially in the proportions of 3 to 1.

RALPH W. AUSTIN.
